UNITED STATES PATENT OFFICE.

FREDERICK J. HARRISON AND WILLIAM J. KNOX, OF DUBOIS, PENNSYLVANIA,
ASSIGNORS TO CAST STEEL PILOT COMPANY, A CORPORATION OF DELAWARE.

LOCOMOTIVE-PILOT.

1,135,521.

Specification of Letters Patent.

Patented Apr. 13, 1915.

Application filed March 7, 1914. Serial No. 823,142.

To all whom it may concern:

Be it known that we, FREDERICK J. HARRISON and WILLIAM J. KNOX, citizens of the United States, residing at Dubois, Pennsylvania, have invented a certain new and useful Improvement in Locomotive-Pilots, of which the following is a full, clear, and exact description, such as will enable others skilled in the art to which it appertains to make and use the same, reference being had to the accompanying drawings, forming part of this specification, in which—

Figure 1 is a front elevational view of a locomotive pilot of our improved construction, the same being applied to a bumper beam. Fig. 2 is a plan view of the pilot applied to a bumper beam with a portion of the latter broken away. Fig. 3 is a side elevational view of the pilot. Fig. 4 is a vertical section taken on the line 4—4 of Fig. 1. Fig. 5 is an enlarged detail section taken on the line 5—5 of Fig. 1. Fig. 6 is a sectional view similar to Fig. 4 and showing a modified construction of the pilot. Fig. 7 is a front elevational view of the upper portion of a modified form of the center section of the pilot. Fig. 8 is an enlarged detail section taken approximately on the line 8—8 of Fig. 7.

Our invention relates to new and useful improvements in locomotive pilots of the general type shown in Patent No. 1,071,155, issued to us August 26, 1913, the principal objects of our present invention being to generally improve upon and simplify the constructions disclosed in the patent aforesaid; to construct a pilot, the main body portion of which consists of a skeleton frame preferably cast, and to combine therewith a separate center section preferably cast, and comprising a coupler pocket, a support for the coupler head, and the center slats for the pilot.

Further objects of our present invention are: to provide a pilot having slats which can be readily detached and replaced in case of breakage; to provide a coupler pocket having a readily detachable plate or bracket which performs the function of a coupler head seat or support; to form integral with the base of the pilot plates which perform the function of steps to enable trainmen to readily mount the pilot and bumper beam, and further to provide a pilot of comparatively simple construction, of great strength

and rigidity, and which can be readily applied to or detached from the locomotive bumper beam.

With the above and other objects in view, our invention consists in certain novel features of construction and arrangement of parts, hereinafter more fully described and claimed.

As shown in the drawings our improved pilot is in the form of a skeleton frame preferably cast in a single piece and comprising a horizontally disposed triangular base 1, a pair of end uprights or posts 2, and a horizontally disposed top rail 3. The end uprights or posts 2 project above the rail 3, and said upwardly projecting portions are fixed in any suitable manner, preferably by means of bolts 4, to the locomotive bumper beam 5. Formed integral with and projecting rearwardly from the upper portions of the posts 2 are brackets 6 which engage the underside of the bumper beam, and are fixed thereto in any suitable manner. Formed integral with the ends of the triangular base 1 and the lower ends of the posts 2 are horizontally disposed plates 7 which constitute steps to permit trainmen to readily mount the pilot and bumper beam.

The upper portion of the rail 3 is cut away at its center as designated by 8 in order to receive the upper portion of a separate center section of the pilot hereinafter described, and to compensate for thus cutting away said top rail, a horizontally disposed flange 9 is formed integral with the lower portion of the center of said rail, which flange projects rearwardly and bears against the underside of the bumper beam 5. The slats 10 of this form of pilot are preferably constructed of wood with their upper ends attached by means of bolts or screws 11 to the rail 3. The lower ends of these slats are attached in any suitable manner to the base member 1, and by reason of the triangular form of said base member, all of the slats occupy inclined positions. The independent center section which includes the coupler pocket, coupler support and center slats of the pilot is formed in a single piece, preferably by casting, and includes a vertically disposed plate 12 which is fixed in any suitable manner to the central portion of the bumper beam 5, and the lower portion of this plate occupies the cut away portion of the top rail 3. Formed integral with and

projecting forwardly from this plate is a housing comprising side walls 12^a, top plate 13, and bottom plate 14, and the space within this housing is adapted to receive the shank of a coupler head. The plates 13 and 14 are perforated so as to receive the coupler head attaching pin. Formed integral with the plate 12 below the bottom plate 14 is a forwardly projecting plate 15 which forms a seat or support for the coupler head. Formed integral with the lower portion of the plate 12 is a depending plate 16 which is attached in any suitable manner, preferably by means of rivets, to the central portion of the member 3 below the opening 8 therein. Formed integral with the plate 12 and housing therein is a downwardly and forwardly projecting skeleton member 17 which forms the center slats for the pilot, and the lower end of this member is attached by rivets or like fastening devices to the central portion of the base 1.

In Fig. 6 we have illustrated a pilot wherein the slats, instead of being constructed of wood, are formed of metal tubes 18, such as old flues, the same being cut into sections of proper length and having their ends flattened and attached by means of rivets or like fastening devices to the top rail 3 and base 1.

In Figs. 7 and 8 we have shown a coupler pocket provided with a detachable coupler support in the form of a plate 19 which is adapted to normally rest upon a pair of lugs 20, which latter are formed integral with the upper portion of the skeleton member 17. These lugs 20 are perforated and receive depending lugs 21 which are formed integral with the plate 19. Formed integral with the rear edge of the plate are upwardly projecting lugs 22 which, when the plate is properly positioned on the member 17, engage behind a portion of the front wall thereof. (See Figs. 7 and 8.)

By virtue of the construction just described, the coupler head supporting plate can be readily replaced in case of breakage.

A pilot of our improved construction is comparatively simple, can be easily and cheaply manufactured, is very strong and rigid, and can be easily applied to a locomotive bumper beam.

It will be readily understood that minor changes in the size, form and construction of the various parts of our improved locomotive pilot may be made and substituted for those herein shown and described, without departing from the spirit of our invention, the scope of which is set forth in the appended claims.

We claim:

1. In a locomotive pilot structure, an integrally formed skeleton frame comprising a triangular base, end uprights, and a top rail, a series of separate inclined slats ar-

ranged between the side portions of the triangular base and the side portions of the top rail, and a separate center section which comprises a coupler pocket and the center slats for the pilot.

2. In a locomotive pilot structure, an integrally formed skeleton frame comprising a triangular base, end uprights, and a top rail, a series of separate inclined slots arranged between the side portions of the triangular base and the side portions of the top rail, and an integrally formed separate center section which comprises a coupler pocket and the center slats for the pilot, which center section is rigidly fixed to the main frame of the pilot.

3. In a locomotive pilot structure, a skeleton frame comprising a triangular base, end uprights, and a top rail, all of which parts are integrally formed, and a separate center section which comprises a coupler shank pocket a coupler head supporting plate and the center slats for the pilot.

4. In a locomotive pilot structure, a skeleton frame comprising a triangular base, end uprights, and a top rail, all of which parts are integrally formed, a series of separate slats arranged between the end portions of the base and the end portions of the top rail, a separate center section comprising a coupler shank pocket a coupler head supporting plate and the center slats for the pilot, which center section is formed in one piece.

5. In a locomotive pilot structure, an integrally formed skeleton frame comprising a triangular base, end uprights, a top rail and a rearwardly projecting pilot beam engaging flange, a series of separate inclined slats arranged between the end portions of the triangular base and the end portions of the top rail, and a separate integrally formed center section, comprising a coupler pocket, a coupler head support, and center slats for the pilot.

6. In a locomotive pilot structure, an integrally formed skeleton frame comprising a triangular base, end uprights, a top rail and pilot beam engaging brackets projecting rearwardly from the end uprights, a series of separate inclined slats arranged between the end portions of the triangular base and the ends of the top rail, and an integrally formed separate center section for the pilot, said center section comprising a coupler pocket, a coupler head support and the center slats for the pilot.

7. The combination with an integrally formed skeleton pilot, of a separate integrally formed center section for said pilot, a coupler shank housing on said center section, and a plate on said center section below said housing, which plate is adapted to receive and support a coupler head.

8. The combination with an integrally formed skeleton pilot, of a separate center

- section therefor, which center section is integrally formed and comprises center slats for the pilot, a housing adapted to receive a coupler shank, and a plate located below and in front of said pocket, which plate is adapted to support a coupler head.
9. In a locomotive pilot, a skeleton frame formed in a single piece and comprising a triangular base, end uprights, a top rail, a 10 pilot beam engaging member projecting rearwardly from the top rail, and pilot beam engaging members projecting rearwardly from the upper portions of the end uprights.
10. In a locomotive pilot, the combination 15 with a skeleton frame formed in a single piece and comprising a triangular base, end uprights and a top rail, of a series of separate inclined slats applied to said skeleton frame between the base and top 20 rail, and a separate center section combined with said skeleton frame, which center section comprises a pilot beam attaching plate, a coupler shank pocket integral therewith, a coupler head supporting plate, and 25 a series of center slats the lower ends of which are adapted to be fixed to the central portion of the triangular base of the pilot frame.
11. In a locomotive pilot, a skeleton 30 frame formed in a single piece and comprising a triangular base, end uprights, pilot beam engaging brackets projecting rearwardly from said uprights, a top rail, a pilot beam engaging flange projecting rearwardly from said top rail, and step plates at the ends of the triangular base, a series 35 of separate inclined slats applied to said skeleton frame between the base and top rail, and a separate center section combined with 40 said skeleton frame, which center section comprises a series of center slats, a coupler pocket, and a coupler head support.
12. The combination with a locomotive 45 pilot, of an integrally formed center section comprising a vertically disposed plate adapted to be attached to a pilot beam, a coupler pocket shank, a coupler head support, and a series of center slats for the pilot.
- 50 13. In a locomotive pilot, an integrally cast pilot section comprising a series of center slats for the pilot, a coupler pocket, and a coupler head supporting plate arranged below and in front of said coupler pocket.
- 55 14. In a locomotive pilot, an integrally cast pilot section comprising a series of center slats for the pilot, a coupler pocket, and a detachable coupler head supporting plate arranged below and in front of said coupler pocket.
- 60 15. In a locomotive pilot, an integrally cast pilot section comprising a vertically disposed base plate, a coupler pocket, a
- coupler head supporting plate arranged below and in front of said coupler pocket, 65 and a series of center slats for the pilot.
16. In a locomotive pilot, the combination with an integrally cast skeleton pilot frame comprising a triangular base, end uprights, a top rail, and steps at the ends of said 70 base of separate slats arranged between the end portions of the triangular base and the end portions of the top rail.
17. In a locomotive pilot, the combination 75 with an integrally cast skeleton pilot frame comprising a triangular base, end uprights, brackets projecting rearwardly from said uprights, and a top rail of separate slats arranged between the end portions of the triangular base and the end portions of the top 80 rail.
18. In a locomotive pilot, the combination 85 with an integrally cast skeleton pilot frame comprising a triangular base, end uprights, a top rail, and a flange projecting rearwardly from said top rail of separate slats arranged between the end portions of the triangular base and the end portions of the top rail.
19. In a locomotive pilot, the combination 90 with an integrally cast skeleton pilot frame comprising a triangular base, steps at the ends thereof, end uprights, brackets projecting rearwardly therefrom, a top rail, and a flange projecting rearwardly therefrom, of 95 separate slats arranged between the end portions of the triangular base and the end portions of the top rail.
20. In a locomotive pilot, an integrally 100 cast skeleton frame comprising a triangular base, end uprights, a top rail, a flange projecting rearwardly from said top rail, and brackets projecting rearwardly from the end uprights, a series of separate slats arranged between the end portions of the triangular base and the end portions of the top 105 rail, and an integrally cast separate center section comprising a pilot beam attaching plate, a housing projecting forwardly therefrom, which housing is adapted to receive 110 a coupler shank, a coupler head supporting plate projecting forwardly from the lower portion of said housing, and a series of inclined slats projecting downwardly and outwardly from said housing, the lower ends of 115 which slats are adapted to be attached to the central portion of the triangular base of the pilot frame.

In testimony whereof we hereunto affix our signatures in the presence of two witnesses, this 23rd day of February, 1914.
